HEAT CONTROL

Wallace C. McAnlis, Detroit, Mich.

Application November 12, 1941, Serial No. 418,680

4 Claims. (Cl. 236—38)

This invention relates to a new and useful improvement in heat control means.

An object of this invention is to prevent the excessive heating of a room and to prevent the waste of heat which is ordinarily occasioned by the occupant opening a window.

A further object of the invention is to control the temperature of a room within close limits, such limits being such as may be desired.

Another object of the invention is to reduce the lapse of time between operation of the heat controls and the change of temperature effected thereby.

Still another object of the invention is to eliminate "hunting" of the controls or in other words the heat is not turned on or off at short intervals of time by reason of over-sensitivity of the controls.

A further object of the invention is to permit heat to be maintained within the radiator when it is not needed to warm the room, and when the heat is later required it may be released.

Another object of the invention is to provide a thermostatic control and a control operable upon opening of the window, which controls operate to open and close a damper in a casing about a radiator.

A further object of the invention is to provide electrical connections and devices to actuate the damper.

Other and further objects and advantages of the invention will become apparent from a reading of the following description in which reference is made to the accompanying drawings, of which there is one sheet, and in which:

Fig. 1 is a perspective view of the invention installed in a room;

Fig. 2 is a side elevational view of a radiator with the device installed therein, being partially cut away in section;

Fig. 3 is a fragmentary view of a window with one of the controls which forms a part of this invention installed therein, the view being partially in section; and

Fig. 4 is a schematic view of the wiring of the invention.

This invention is applied to a radiator 10 of conventional type, which, because of the nature of this invention, need have no valve or manual control attached thereto to control the flow of heating fluid therethrough. Because it is not necessary to open and close any valve in the steam or hot water supply lines to the radiator, the functioning of the heating system is improved

in that in common controls of radiators opening and closing the valve permits air to enter in the system, which causes air pockets. Air pockets sometimes prevent the return of the heating fluid to the radiator when the valve is re-opened, cause corrosion of the pipes, cause objectionable noises or "hammers" and cause discomfort and annoyance to the occupant of the room. The radiator is enclosed in a casing 12, which may be insulated by heat-insulating material 14 so as to retain heat within its walls. An opening 16 is provided at the top of the casing 12, and a damper 18 fits within the opening 16 so that when the damper 18 is closed no heat may escape from the top of the casing 12. Another opening 20 is provided in the bottom of the casing 12 to permit the circulation of air past the radiator 10.

A crank 24 is attached to the damper 18 so that rotary movement of the crank 24 causes the damper 18 to open and close. The crank 24 has a pin 26 attached thereto which fits within the slot 28 in the core 32 of the vertically mounted solenoid 34. A spring 35 is attached at one end to the core 32 and at the other to the crank 24.

When the damper 18 is open and electric current flows through the coil 36 of the solenoid 34, the core 32 is attracted and pulled upward. This results in placing tension on the spring 35 and pulls the crank 24 upward, after cushioning the force of the magnetic attraction of the core 32. When the damper 18 is closed and electric current ceases to flow through the coil 36, the force of gravity acts upon the core 32 and it descends. The upper end of the slot 28 acts upon the pin 26 and causes rotation of the crank 24 to close the damper 18.

The damper 18 will normally be open so long as there is current flowing through the coil 36 and will be closed when there is no current through the coil 36.

A thermostat 38 is installed on one wall of the room being so designed that the bi-metallic element 40 will expand when the temperature rises, and when it rises above a predetermined temperature will break the connection with the contact 42 so that current will cease to flow from the lines 43 through the coil 36. Thereupon the core 32 will fall by gravity and the damper 18 will be closed. Thereafter no heat will be released from the radiator 10 into the room even though heating fluid such as steam continues to flow through the radiator 10. When the temperature drops so that the element 40 engages the contact 42, current flows through the coil 36, the core 32 is

attracted and raised and the damper 18 restored to open position unless control 44 has broken the circuit as will be described.

Another control 44 is provided on the window frame 46 in series with the thermostat 38 operable so that when the sash 48 is moved to open position the circuit through the coil 38 will be broken and thereby the damper 18 closed. This prevents wastage of heat through an open window, which would otherwise occur if the thermostat 38 were not immediately adjusted to a lower temperature. It will be apparent that this invention finds particular adaptation in hotel rooms and other places where economy is not of primary concern to the occupant.

The control 44 comprises a casing 50 which is attached to the window frame 46. A wire 52 of the circuit above discussed is attached to one insulated binding post 54 and a second wire 56 is attached to a second insulated binding post 58. An electrical contact 60 is fixed to the second binding post 58, and an electrical contact 62 is attached to a leaf spring 64 which is attached to the first binding post 54. An abutment 66 is likewise attached to the spring 64. The abutment 66 projects out from the casing 50 into the path of the sash 48 so that when the sash 48 is open beyond a predetermined distance the abutment 66 is depressed, breaking contact between the contacts 60 and 62 thereby breaking the circuit. When the sash is shut, the spring 64 causes contact between contacts 60 and 62 and the abutment 66 is forced into the path of the sash 48. However, so long as the window is open more than a predetermined distance, the circuit is broken.

It will be observed that whenever the temperature of the room is above a predetermined amount, the thermostat 38 operates to break the circuit and thereupon the damper 18 is closed, and whenever the sash 48 is opened more than a predetermined distance the control 44 likewise breaks the circuit and the damper 18 is closed. When the sash 48 is open less than the predetermined distance and the temperature is below the predetermined amount, the circuit is closed and the damper 18 is open.

The control 44 may be made adjustable by providing slots 68 in the casing 50 through which screws 70 project into the window frame 46. As will be observed, the casing 50 may be slid up and down within the limits of the slots 68. Thereafter the screws 70 may be tightened to hold the control 44 in fixed position. This adjustability is provided so that the distance which the sash 48 may be opened before the control 44 operates to close the dampers 18 and 22 may be varied as desired (or if installed in a hotel, may be adjusted by the management).

Whereas, I have specifically pointed out, illustrated and described my invention, nevertheless, it will be understood that certain modifications may be made therein without departing from the spirit of the invention as set forth in the appended claims.

What I claim is:

1. In a heat control, a source of heat, a casing about said source of heat, a damper in said casing, a solenoid coil, a core in said solenoid coil connected to said damper to open said damper, control means breaking the circuit through said solenoid coil upon opening of a window beyond a predetermined amount, and thermostatic control means breaking the circuit through said solenoid coil upon room temperature exceeding a predetermined amount.

2. In a heat control, a source of heat, a casing about said source of heat, a damper in said casing gravity biased to closed position and operated by electrical means to open position, a resilient abutment extending into the path of a window sash to break the electrical contact in said electrical means upon opening of the window sash beyond a predetermined amount, permitting gravity to close said damper upon opening of the window sash beyond the predetermined amount.

3. In a heat control, a source of heat, a casing about said source of heat, heat-insulating material lining said casing, a damper in said casing gravity biased to closed position and operated by electrical means to open position, control means non-operable upon opening of a window beyond a predetermined amount to interrupt the electrical means and permit gravity to close said damper, and thermostatic control means to interrupt the electrical means to close said damper upon room temperature exceeding a predetermined amount.

4. In a heat control, a source of heat, a casing about said source of heat, a damper in said casing gravity-biased to a closed position and operated by electrical means to open position, a resilient abutment extending into the path of a window sash operable to break an electrical contact in said electrical means upon opening of the window sash beyond a predetermined amount to close said damper and to make an electric contact in said electrical means upon closing of the window sash and thermostatic means to control said electrical means when said electrical contact is closed to open and close said damper dependent upon the room temperature being above and below a predetermined temperature degree.

WALLACE C. MCANLIS.
